(57) **CLAIM**

The ornamental design for an automobile front lower fascia, as shown and described.

DESCRIPTION

FIG. 1 is a perspective view of an automobile front lower fascia showing my new design;

FIG. 2 is a front view thereof;

FIG. 3 is a left side elevation view thereof (where the right side elevation view is omitted since the right side elevation view is a mirror image of the left side elevation view); and, FIG. 4 is a bottom plan view thereof.

The broken lines in the drawings illustrate portions of the automobile front lower fascia that form no part of the claimed design.
